UNITED STATES PATENT OFFICE.

WILLIAM E. CLARKE, OF OAKLAND, CALIFORNIA.

DESIGN FOR A FRATERNITY-EMBLEM.

45,288.

Specification for Design.

Patented Feb. 24, 1914.

Application filed January 5, 1914. Serial No. 810,516. Term of patent 3½ years.

To all whom it may concern:

Be it known that I, WILLIAM EDWARD CLARKE, a citizen of the United States, residing at Oakland, in the county of Alameda and State of California, have invented a new, original, and ornamental Design for Fraternity-Emblems, of which the following is a specification, reference being had to the accompanying drawing, forming part thereof.

The figure is a plan view of a fraternity emblem, showing my new design.

I claim:—

The ornamental design for a fraternity emblem, as shown.

In testimony whereof I affix my signature in presence of two witnesses.

WILLIAM E. CLARKE.
